WARDROBE CASE SECTION CLOSURE FLAP

Julius Ritter, Jr., Racine, Wis., assignor to Hartmann Trunk Company, Racine, Wis., a corporation of Wisconsin

Application April 13, 1940, Serial No. 329,399

1 Claim. (Cl. 190—41)

This invention relates to improvements in wardrobe case section closure flaps.

In certain wardrobe cases of the hand luggage type, particularly adapted for ladies' garments, the cover sections are equipped with fixtures for folding and compacting dresses and like garments to house the same primarily within the cover sections of the cases. Flexible retainer curtains are secured in a manner so as to be extended over the packed garments to cover and protect the same and to segregate these garments from those packed within other portions of the luggage case. A retainer curtain of the type mentioned usually has one of its edges permanently secured within one end of the case section, and for covering purposes the opposite end is detachably secured within the opposite end of said case section. Consequently, a curtain arrangement of this type is only practical and suitable where it is convenient to completely close the said section of the luggage case, and the use of the curtain prohibits extension of garments beyond the outline of the cover of the case into, for instance, a portion of the body of the case.

It is, therefore, the primary object of the present invention to overcome the above objections or limitations by providing a container section closure flap or curtain which is securable over the open face of a container section, to completely cover and protect garments within said section, but which will, when extended, permit the draping of end portions of long garments into a portion of the other section of the luggage case.

A further object of the invention is to provide a container section closure flap which will function in the usual manner, but which will, moreover, permit long garments to extend beyond the section covered by the curtain, and which will cover and protect extended portions of such garments and prevent the same from catching in any of the hinged elements of the luggage case.

A further object of the invention is to provide an improved permanent means of attachment between one end of a closure flap or curtain and the inner end of a luggage case section; with said means of attachment permitting the formation of a slit or opening at said end of the curtain.

A further object of the invention is to provide a wardrobe case closure flap or curtain which is attached to a case section in a manner so as to provide a main curtain portion for the case section, and an auxiliary protective flap portion effective in another part of the wardrobe case.

A further object of the invention is to provide

a wardrobe case including a garment folding and compacting frame and a closure flap or curtain, the frame being pivotally mounted within the inner end of the cover of the case and having its inner end equipped with detachable mounting means for individual garment bars, and the closure flap or curtain being secured within the inner end of the cover by attaching means extending inwardly of the inner ends of the frame, and spacedly from the garment bar mounting means.

Still another object of the present invention is to provide a wardrobe case structure, including a closure flap or curtain for one of the case sections, which is of very simple construction and is inexpensive to manufacture.

These and other objects and advantages of the invention will be apparent from the following detailed description.

A clear conception of an embodiment of the invention may be had by referring to the drawing accompanying and forming a part of this specification in which like reference characters designate the same or similar parts in the various views:

25 Fig. 1 is a transverse sectional view through an open wardrobe case, showing the garment folding frame positioned over the body section of the case preparatory to loading and folding garments, and showing the improved closure flap or curtain in its released and inoperative position;

30 Fig. 2 is a similar transverse sectional view through the open case showing the garment supporting frame in loaded position within the cover section of the case and showing the closure flap or curtain engaged and closing the open face of the cover section of the case;

35 Fig. 3 is an enlarged fragmentary plan view, partly in section, showing the case sections open, the frame in lowered position, and the attaching means for the inner end of the closure flap or curtain;

40 Fig. 4 is an enlarged fragmentary vertical sectional view showing the mounting means for the individual garment bars at the inner end of the frame and the curtain in its released and inoperative position; and

45 Fig. 5 is a similar view showing the manner in which the ends of the individual garment bars are engaged or disengaged with the holding means therefor on the inner end of the frame.

50 While the invention has been shown and described herein as being applied, by way of illustration, to a relatively small and light luggage or wardrobe case for ladies' garments, it should be understood that some of the novel features

are more generally applicable to other types and classes of luggage carriers, and it is not the intent to limit the invention by such specific disclosure.

The improved wardrobe case illustrated in the drawing comprises in general a body section 8 having a cover section 9 pivotally or hingedly connected thereto by means of a hinge strip at the meeting inner end portions of the body and cover sections. The garment folding and confining mechanism is mounted entirely within the cover section 9, but the garment folding frame is adapted to be moved down to extend over the body section 8, as in Fig. 1, for loading purposes. The body section 8 may be provided with the usual carrying handle 10, and the cover section 9 may be swung into engagement with the body section and locked thereto by means of the usual latches 11. The cover section 9 is held in substantially upright position when the body section 8 is disposed horizontally and the cover section 9 is in open position, by means of foldably connected stays or retainers 12 of the usual type.

The improved garment folding and supporting fixture comprises generally a garment folding frame 13 having the extreme inner end portions of its side arms outwardly offset or flanged and supported by means of pivots 14 upon the inner side walls of the cover section 9 near the hinge connection of said cover section with the body section. The frame 13 has an integral transverse garment folding bar 15 connecting the outer ends of the side members of the frame and remote from the pivots 14. The inner side wall portions of the body section 8 of the case are provided with cleats 16 upon which the outer end of the frame 13 is supported when the frame is in its horizontal position.

The inner end of each side arm 17 of the frame has secured thereto the short side of a U-bracket 18. The U-brackets are secured to the arms 17 in a manner so that the sides of the U-brackets are perpendicular to the arms 17. The free ends or arms 19 of the brackets 18 are relatively long and have outwardly flared curved and grooved guide ears 20 at their free extremities. The main extents of said bracket portions 19 have elongated slots 21 therein. The arms 19 of the brackets 18 are furthermore of spring metal and are yieldable. When the frame is in the horizontal position of Fig. 1, said bracket arms 19 project vertically upwardly, while when the frame is in its vertical position within the cover of the case, said arms 19 of the brackets project transversely of the inner end of the cover, as in Fig. 2. It will thus be seen that the yieldable and slotted arms 19 of the brackets 18 are carried directly by the inner ends of the arms 17 of the frame 13. Said bracket arms 19 provide means for mounting, on the inner end of the frame, a plurality of superimposed individual garment bars 22. Each bar 22 is formed with reduced stub ends 23 to engage and move in the slots 21 of the bracket arms 19. Said stub ends, being flattened, coact with the slots 21 in a manner to prevent rotation of the bars relative to the brackets 18, while permitting movement of the bars longitudinally of the slots.

When it is desired to load the improved wardrobe case with garments, the garment bars 22 are first removed and the individual garments are folded over said bars which are then inserted in the bracket arms 19 in stacked relationship, as in Fig. 1. The frame 13 is disposed as shown and the ends of the garments extend out over the frame and forward end of the body section of the

case. The frame 13 may then be swung upwardly away from the cleats 16, whereupon the transverse bar 15 becomes effective to fold the garments intermediate the extremities of the same and to impose secondary folds therein. The frame 13 is swung to the position of Fig. 2 entirely within the open cover section of the case, and if the garments or dresses are rather long, extended end portions of the same are accommodated within the inner end of the body section 8 of the wardrobe case. This is when the particularly advantageous features of the improved closure flap or curtain come into play.

The curtain or flap is designated generally by the numeral 24. This curtain or flap is of fabric and is flexible and may preferably be formed of several plies of the fabric. Its outer or free end portion encloses a rigid transverse strip 25 to which is secured, medially of its ends, a strap carrying one element 26 of a clasp device. The longitudinal dimension of the flap or curtain 24 is substantially greater than that of the cover section 9 which it is adapted to close. Substantially midway between the transverse center line of the curtain 24 and its depending lower or inner edge, flexible securing straps 27 have portions sewed or otherwise secured to side edge portions of the curtain 24. The opposite ends of said straps 27 are permanently secured to inner surface portions of the rear wall of the cover section 9, as at 28. It will thus be seen that side edge portions of the curtain 24 substantially inwardly of the inner edge of said curtain, are attached to the inner rear wall of the cover section 9 of the case. When the fixture or frame 13 is loaded with long garments and manipulated in the manner previously described, it moves into the cover of the case, as in Fig. 2. Initially the upper or outer end of the curtain 24 is released and the curtain is disposed in the inoperative position illustrated in Fig. 1. However, when the cover section of the case becomes loaded in the manner described, it is desirable to secure the curtain 24 over the open face of the cover section 9 to cover and protect the garments on the frame 13 and to hold and maintain the frame and garments thereon within the cover section 9. For this purpose the element 26 of the clasp is engaged with a complementary clasp element 29 secured within the outer or free end of the cover section 9. The transversely spaced apart straps 27 then serve to secure a lower portion of the curtain adjacent the inner end portion of the cover, and the larger portion of the curtain or flap 24 is tautly applied over the open face of the cover and serves its function in the usual manner. However, that portion of the curtain inwardly of the securing straps 27 forms an auxiliary depending flap which drapes into the inner end of the body section 8 of the case. If the garments on the frame 13 are long, end portions of the same may extend downwardly into the rear end of the body section of the case, as depicted in Fig. 2, said extended end portions of the garments being accommodated between the spaced straps 27 and being substantially covered and protected by the depending flap portion of the curtain 24. Therefore, the manner in which said curtain is constructed and secured permits it to serve a two-fold purpose. It covers the open face of the cover section 9 in the usual manner and it also provides an auxiliary flap extending into the body section of the case for covering and protecting extended end portions of garments. The securing means for the inner portion of the curtain is such that a

space is provided to permit the extension of the end portions of the garments from the cover section into the body section of the case.

The improved curtain, and its mode of attachment, is effective in view of the simple form of the frame 13 utilized, wherein the mountings for the individual garment bars 22 are carried directly by the frame and said elements, including the pivots of the frame, are located substantially away from the points of attachment of the curtain 24. The movable parts of the frame will not catch or engage the curtain, and furthermore sufficient clearance is provided for the extended end portions of the long garments. If the garments on the frame 13 are accommodated entirely within the cover section 9 of the case, then the inner extended flap portion of the curtain merely drapes against the inner rear wall of the body section 8 of the case, and only becomes effective when it is required for long extended garment portions.

From the foregoing description it will be apparent that the improved wardrobe case section closure flap is simple, easily manipulated and inexpensive. Its connection with the cover section of the case is such as to permit clothes to be extended beyond the cover section of the case and thereby differs from the usual form of container section curtains and the manner in which they are attached.

It should be understood that it is not desired to limit the invention to the exact details of construction herein shown and described, for various modifications within the scope of the claim may occur to persons skilled in the art.

What is claimed as the invention is:

In a luggage case, a body section, a cover sec-

tion having a rear wall thereof hingedly connected to an adjacent wall of the body section, a fixture for folding and compacting garments, said fixture including a frame having its inner ends connected by pivots to inner wall portions of the cover section slightly spaced outwardly of the hinged wall of the cover section, inner end portions of the frame having garment folding bars removably mounted directly thereon, substantially spaced from the hinged wall of the cover, the ends of said bars terminating short of the sides of the cover section, said fixture being adapted to swing into the cover section of the case to house folded garments within said cover section, a flexible curtain for closing the open face of the cover section, elongated flexible transversely spaced apart straps having their ends attached respectively to intermediate side portions of the curtain and to spaced end portions of the hinged rear wall of the cover, the connections of said straps with the cover being removed from the pivotal connections of the fixture frame and from the bars carried by the inner end of said frame, said curtain being of substantially greater height than the cover section, and clasp members detachably connecting the outer end of the curtain to the free end of the cover section, the inner end portion of the curtain, beyond said straps, forming a foldable flap depending a substantial distance into the rear of the body section of the case to accommodate between it and wall portions of the case extended end portions of garments draping from the cover section into the body section of the case.
